HIGH VELOCITY DRYER TUBE

Alfred G. Russell, Martinsville, N.J., assignor to Frank W. Egan & Company, Somerville, N.J., a corporation of New Jersey

Filed Mar. 27, 1961, Ser. No. 98,387

5 Claims. (Cl. 34—160)

This invention relates in general to apparatus for treating strip or web material such as fabrics, papers, pulp and other liquid containing or coated materials, by means of a fluid such as steam, air, or other gases, and more particularly the invention is directed to apparatus such as high velocity dryers that include large conduits or headers for supplying the treating fluid such as air, and elongated fluid-distributing tubes, each having at least one inlet end connected to and communicating with at least one of the headers or conduits and also having restricted outlet openings spaced apart longitudinally of the tube or an elongated outlet slot extending longitudinally of the tube for directing the treating fluid at high velocity onto the web, sheet, or strip to be dried or otherwise treated. The invention especially contemplates an improvement in fluid-distributing tubes for apparatus of the type described in my co-pending application Serial No. 968, now Patent No. 3,036,385, filed January 7, 1960, wherein there are a plurality of elongated air-distributing tubes in a housing that are rectangular in cross-section and are closely spaced from each other, each with an inlet at one end connected to and communicating with a fluid supply header and having a plurality of outlet slots in one wall thereof aligned longitudinally of the tube so that fluid is conducted from the supply header to the material being treated and flows after contact with the treated material between the tubes and thence into the atmosphere, for example, through exhaust ducts or plenums.

It has been noticed in the use of the tube type high velocity drying system that there is a temperature inequality of the supply air due to the very large heat transfer rates possible with this type drying system. There are two important temperature difference with which the present invention is concerned, one difference being between the air inside the distributing tube and the spent air outside the tube after the air has contacted the web; and the other temperature difference occurs in the supply air inside the distributing tube between the feed or inlet and the portion of the outlet farthest from the inlet. With end fed tube type drying systems, the supply air impinges on the web, then passes between successive tubes back to the exhaust and recirculation plenums. Prior experience has not brought this inequality to light inasmuch as the drying efficiency of earlier systems did not approach that of the presently known systems, in operation of which with high drying loads, the temperature of fluid issuing from the outlet slots at the header end of the tube may be as much as 30° to 40° F. higher than that issuing from the closed end. When highly efficient drying means possible with known high velocity tube type drying systems are subjected to heavy drying loads, i.e., are used to evaporate large quantities of water from a web, there is a significant heat transfer between the supply air and the web. This causes a drop in the temperature of the supply air relative to the temperature of the exhaust air that can be as high at 100° to 200° F., depending upon the initial temperature. This is one temperature difference between the air inside and the spent air outside the tube causes a heat transfer between the tube walls which results in loss in temperature of the supply air. Another temperature difference which may be of the order of about 70 degrees occurs in the sup-

2

ply air in the distributing tube between the feed or inlet and the portion of the outlet farthest from the inlet; in other words, the air which issues from the outlet slot, the farthest from the inlet end has to pass a greater distance along the relatively cool outer walls, and therefore gives up more heat, resulting in lowering of its temperature relative to the supply air which issues from the slot nearest the feed end. The use of end fed tubes wherein the spent air passes from the web between successive tubes improves the air flow characteristics in the drying of continuous webs, and the present invention permits the use of this efficient tube fed drying means in applications where high drying rates are experienced. The present invention includes alternate methods of correcting this inequality, based on the anticipated heat transfer and resultant temperature difference between the supply and exhaust air, to insure essentially equal supply air temperatures across the width of the slot irrespective of the difference in supply and exhaust air temperature.

It will also be understood by those skilled in the art that it is desirable that the velocity of the fluid be substantially uniform at the outlets so that the portions of the material being treated that lie farthest from the inlet of the tube will be subjected to essentially the same temperature and velocity of air as the other portions of material nearer the inlet.

Therefore, primary objects of the present invention are to provide apparatus of the character described including a fluid-distributing tube constructed in a novel and improved manner providing for substantially equal or uniform fluid temperature at all of the discharge openings throughout the length of the tube; and to provide such a tube, the construction of which shall be such that the equality or uniformity of the fluid temperature shall be obtained without material effect upon the velocity of flow of the fluid from the outlets.

Further objects are to provide an air-distributing tube of the character described which shall have therein a novel and improved baffle disposed between the inlet and the outlet of the tube such that the length of the path of travel of the fluid from the inlet to the outlet shall be different at different zones in the length of the tube, and thus to provide in the tube a baffle which shall cause the fluid emerging from the outlets nearer the inlet to travel from the inlet to the outlet a greater distance along the relatively cool outer wall of the tube than does the fluid emerging from the zone of the outlet farthest from the inlet and thereby equalize the cooling effect on the air issuing from the tube at all points along the length of the tube.

Still another object is to provide such a tube wherein the baffle is so constructed and arranged as to insulate the warm fluid within the tube against the cooling effects of the fluid that flows outside and between the tubes from contact with the material being treated to the exhaust ducts, particularly where the temperature difference between the supply air and the outside air is relatively small.

Other objects, advantages and results of the invention will be brought out by the following description in conjunction with the accompanying drawings in which:

FIGURE 1 is a schematic transverse vertical sectional view through a high velocity tube-type dryer including a housing in which are a plurality of fluid-distributing tubes embodying the invention, said figure being similar to FIGURE 1 of my above-mentioned co-pending application, Serial No. 968;

FIGURE 1A is a schematic sectional view approximately on the plane of the line 1a of FIGURE 1;

FIGURE 2 is an enlarged perspective view of a fluid-distributing tube removed from the housing shown in

FIGURE 1 and with portions broken away and other portions shown in section for clearness in illustration;

FIGURE 3 is a further enlarged transverse vertical sectional view approximately on the plane of the line 3-3 of FIGURE 2;

FIGURE 4 is a similar view on the plane of the line 4-4 of FIGURE 2;

FIGURE 5 is a view similar to FIGURE 4 on the plane of the line 5-5 of FIGURE 2;

FIGURE 6 is a central longitudinal vertical sectional view through a fluid-distributing tube embodying a modified form of the invention, the baffle being shown in side elevation with portions broken away;

FIGURE 7 is an enlarged transverse vertical sectional view on the plane of the line 7-7 of FIGURE 6;

FIGURE 8 is a view similar to FIGURE 6 showing another modification of the invention;

FIGURE 9 is an enlarged transverse vertical sectional view of the whole tube on the plane of the line 9-9 of FIGURE 8;

FIGURE 10 is a similar view on the plane of the line 10-10 of FIGURE 8;

FIGURE 11 is a view similar to FIGURE 8 showing another form of the invention;

FIGURE 12 is an enlarged transverse vertical sectional view through the whole tube approximately on the plane of the line 12-12 of FIGURE 11;

FIGURE 13 is a view similar to FIGURE 11 showing another modification of the invention; and

FIGURE 14 is a view similar to FIGURE 2 on the plane of the line 14-14 of FIGURE 13.

While the invention has been illustrated in connection with the generally known type of apparatus for drying or otherwise treating strip materials or webs, it should be understood that the invention may be embodied in other types of fluid-distributing tubes for other material treating apparatus, and while the fluid-distributing tube embodying the present invention has been shown in conjunction with apparatus like that shown in my co-pending application wherein the material to be treated is in the form of an elongated web moved by an endless conveyor through the housing between two banks of distributing tubes, the invention resides in the construction of a single tube which may be used alone or in conjunction with other tubes for drying, for example, webs or strips moved on conveyors or separate pieces placed in and removed from the dryer housing manually or in some other way.

Specifically describing the embodiment of the invention illustrated in FIGURES 1 through 6, the reference character A generally designates a housing or casing providing therein a treatment chamber through which a strip or web of material B is conveyed in horizontal position by a suitable conveyor which in the present instance is shown as including two horizontally spaced chains C slidably mounted on tracks D within the housing and driven by suitable means such as sprockets G and power operated drive means such as a motor (not shown), the chains supporting cross bars E that are spaced apart longitudinally of the chains and may have connected thereto helical springs F or the like on which the web B is laid so that there is a minimum of area of contact between the web and the conveyor. One track D is shown as mounted on a vertical frame piece 1 in the housing while the other track D is shown as mounted on the inner side of one of two supply conduits or headers H for the treating fluid such as steam or air.

While in many cases only one bank of fluid-distributing tubes is required, in the present instance, two horizontal banks of tubes I and I' have been shown, one bank above and one bank below the web B, and each of the tubes of one bank has one end connected to one of the headers H while each tube of the other bank has one end connected to the other header H'; and the treating fluid is conducted from the headers through the respec-

tive tubes I and I' and their outlets J into contact with the corresponding sides of the web B, whereupon the treating fluid passes into outlet or exhaust ducts K and K' through slots K".

5 While the tubes may be mounted in any suitable manner in the housing and connected to the supply pipe or header in different ways, for the purpose of illustration here, each tube is removably mounted in the apparatus and has one end held in separably connected relation to the corresponding header under yielding or spring pressure.

As shown in my co-pending application, one vertical wall 2 of each header has an opening 3 therein to receive each tube, and each tube has a stop member or flange 4 in spaced relation to the end of the tube to abut the side wall of the header and limit insertion of the inlet end of the tube into the opening 3 as best shown in FIGURES 1 and 6.

15 The other end of each tube is separably connected to the support frame by a connector device L.

As will be readily understood by those skilled in the art, access to the tubes for insertion and removal thereof may be had through a suitable access opening A' that is normally closed by a door A".

20 The construction of the fluid-distributing tube I may be varied, but as shown, the tube is rectangular in cross-section and has an end wall 6 opposite the inlet end, side walls 11, a top wall 12, and a bottom wall 13 intermediate the width of which is a discharge opening or outlet 14 which is formed by integral parallel lips 14 projecting from the bottom wall and rigidly held in pre-determined spaced apart relation by spacer blocks 15 that are disposed in spaced relation to each other longitudinally of the lips. With this construction, a portion of the outlet 25 of each tube comprises an outlet or discharge opening between each two adjacent spacer blocks but the openings are closely spaced and staggered in successive tubes so that, in effect, there will be a substantially continuous sheet of warm fluid discharged from each tube into contact with the sheet or web of material B being treated.

25 Obviously, the dimensions of the tubes will vary according to the conditions of intended use, as will also the lips 14 and the spacing of the blocks 15. The ratio of cross-sectional area of the tube to the area of the discharge openings may be varied but preferably is such as to obtain substantially equal or uniform fluid distribution through the discharge openings along the length of the tube. Experience shows that desirable ratios are of 2.5/1 upward to 10/1, the most desirable ratio being between 5/1 and 8/1.

50 It will be noted that the plurality of tubes I in a bank are closely spaced apart and that the fluid discharged from the discharge opening J contacts with the material being treated and gives up heat which reduces its temperature whereupon it flows between the tubes to the exhaust ducts 55 as shown schematically in FIGURE 1a and thus produces a cooling effect on the fluid in the tubes; and it will also be observed that unless some means is provided to prevent it, the temperature of the fluid in the tube will gradually decrease during the flow of the fluid from the inlet end of the tube to the opposite end thereof. It should be understood that the cooling effect is a relative matter and there will be heat transfer and temperature inequality, for example, with a supply air temperature of 700° F. which cools to 600° F., and there will also be heat transfer and temperature inequality where the supply air has a temperature of 170° F. and is cooled to 70° F. The differences in temperature between the supply air and the exhaust air with known constructions is most likely to occur where a heavy drying load is impressed upon the drying apparatus.

55 As hereinbefore indicated, the invention provides a fluid-distributing tube embodying a novel and improved construction which will ensure substantial equal or uniform temperature of the fluid flowing from the discharge

openings of the tube throughout the length of the tube, and more particularly, the invention contemplates a baffle that is inserted into the tube. One form of the invention is shown in FIGURES 1 through 5 inclusive where the baffle comprises a rectangular tube M open at one end and having a wall M' at its other end, side walls 16 and 17, a top wall 18, and a bottom wall 19, all preferably in equidistantly spaced relation to the corresponding walls of the tube I. The inlet end of the baffle tube has an exterior perimetral flange 20 snugly fitted within the tube I so as to close the space between the walls of the two tubes and ensure that fluid shall flow from the supply header only into the baffle tube. The baffle tube has outlet apertures 21 arranged in its walls so that the fluid from inside the baffle tube will flow through said apertures into the spaces between the baffle tube and the distributing tube and the length of the path of flow of the fluid from the outlet apertures 21 to the discharge openings J will vary between the inlet of the distributing tube and the other end thereof. Thus, a series of outlet apertures 21a is provided in the top wall 18 of the baffle tube adjacent the inlet of the distributing tube, another series 21b of outlet apertures are formed in the side walls 16 and 17 of the baffle tube and extend in an approximately straight line from the top wall to the bottom wall as best shown in FIGURE 2, to a point in spaced relation to the closed end of the distributing tube; and a third series 21c of outlet apertures is provided in the bottom wall 19 of the baffle tube between the apertures 21b and the end of the tube. The rows of apertures 21a and 21c also preferably extend diagonally from the side walls to the centers of the top and bottom walls, respectively. With this construction, it will be observed that the path of flow of fluid along the relatively cool outer walls 11, 12 and 13 from the apertures 21a to the discharge openings J will be substantially greater than the distance of travel of the fluid along said cool outer walls from the outlet apertures 21c to the discharge openings J, and the distances of travel along said cool outer walls from the apertures 21b to the discharge openings J will gradually decrease from the apertures 21a to the apertures 21c. These paths of flow are indicated by the arrows in FIGURES 3, 4 and 5 of the drawings.

A modified form of the invention is shown in FIGURES 6 and 7 wherein the baffle insert N is in the form of a channel having a continuous flange 22 at one end corresponding to the flange 20 and having its bottom wall 23 parallel and in spaced relation to the bottom wall 13 of the distributing tube I with its side walls 24 disposed in spaced and parallel relation to the corresponding side walls of the distributing tube I and gradually decreasing in height or width from the inlet end of the distributing tube to the opposite or closed end 6 thereof. Desirably, the end of the bottom wall 23 of the baffle insert may have an extension tongue 25 secured to the end wall 6 for supporting that end of the baffle.

With this construction, it will be observed that the fluid will flow from the header into the baffle N and upwardly over the edges of the side walls 24 of the baffle and thence downwardly to the discharge openings J of the distributing tube as schematically illustrated by the arrows in FIGURE 7; and due to the decreasing height of the side walls 24, the lengths of the paths of flow of the fluid from the inlet end of the distributing tube to the discharge openings J adjacent said inlet end will be substantially greater along relatively cool surfaces 11 than the lengths of the paths of flow of the fluid from the channel of the baffle over the edges of the side walls thereof to the discharge openings at the other end of the distributing tube.

FIGURES 8, 9 and 10 show another form of the invention where one of the distributing tubes I' is illustrated with its discharge openings J facing upwardly instead of downwardly as in tubes I in FIGURES 1 through 7 inclusive. In this form of the invention, the baffle O is shown as comprising two side walls 27 extending through-

out the length of the tube having flanges 28 at their longitudinal edges to space the side walls 27 from the corresponding walls of the distributing tubes I'.

There is a partition 29 connecting and between the side walls throughout about half the length and about centrally of the height thereof. A vertical partition 30 extends between the inlet end of the baffle, the side walls 27, and the bottom wall of the distributing tube. With this construction, the fluid from the header flows through 10 the inlet of the distributing tube between the partition 29 and the wall of the distributing tube opposite the discharge openings as indicated by the arrows in FIGURE 8. Some 15 of the fluid continues to flow toward the closed end of the distributing tube while the direction of flow of the other portions of the fluid is reversed so that said portions 20 flow backwardly along the partition 29 and outwardly through the discharge openings J, all as indicated by the arrows in FIGURE 8. Thus, the difference in distance and direction of flow of the fluid at different points in 25 the length of the tube and the insulating spaces between the tube walls 11 and baffle walls 27 ensure that the temperature of the fluid throughout the discharge openings J shall be substantially uniform.

As above stated, the spaces between the side walls 27 25 of the baffle O and the corresponding side walls of the distributing tube serve as insulating spaces, and it will be observed that in addition to the variations in the length and direction of the paths of flow of the fluid for providing essentially uniform temperature of the fluid in all of 30 the discharge openings, other forms of the invention also utilize the insulating property of some of the spaces between the walls of the baffle and the walls of the distributing tube to reduce the cooling effect on the fluid in the tubes of the fluid flowing along the outer sides of the 35 walls of the tubes. For example, in the form of the invention shown in FIGURES 1 to 5 inclusive, the space between the side walls 16 of the baffle tube and the side walls 11 of the distributing tube, as well as the spaces between the side walls 18 and the top wall 12 of the 40 distributing tube between the outlet apertures 21a and the closed end of the distributing tube, insulate the walls 16 and 18 of the baffle tube against the relatively cool air in contact with the outer surface of the side walls 11 and top wall 12 of the distributing tube.

FIGURES 11 and 12 show another form of the invention somewhat similar to the form shown in FIGURES 8 to 10 inclusive except that the side walls 32 of the baffle P extend the full length of the distributing tube and the partition 33 extends throughout the length of the distributing tube and is inclined from the inlet end of the tube toward the opposite end thereof in such a way that the volume of the space for flow of fluid from the inlet through the discharge openings decreases gradually from the inlet end of the tube to the opposite end thereof. The 55 spaces between the side walls 32 of the baffle and the corresponding side walls of the distributing tube serve as insulating spaces.

FIGURES 13 and 14 show still another form of the invention wherein the baffle Q comprises two side walls 34 similar to the side walls 32 that are spaced from the corresponding side walls of the distributing tube and are connected adjacent their upper ends by a partition 35 that extends from the inlet end of the baffle to a point spaced from the opposite end thereof at which there is another partition 36 in spaced relation to the end wall 6 of the distributing tube. At the inlet end of the baffle is a flange 37 that closes the space between the side walls of the distributing tube and the baffle and between the top wall of the distributing tube of the partition 35 of the baffle. With this construction, there are insulating spaces between the top wall of the distributing tube and the partition 35 of the baffle, also between the side walls of the baffle and the side walls of the distributing tube and between the end wall of the distributing tube and the partition 36.

While the fluid-distributing tubes embodying the invention may be satisfactorily used under different conditions, it can be said that the invention has been found especially satisfactory in tubes having a discharge slot or opening about ninety inches in length and operating with an air temperature difference up to 220° F. between the air supply at the inlet and the ambient air outside the tubes, giving less than a 5° F. temperature difference between the end of the discharge opening nearest the tube inlet and the opposite end of the tube. Without the baffles, the temperature difference may be as great as 50° F. Furthermore, from experience with the form of the invention shown in FIGURES 6 and 7, it has been found that the air velocity profile gives a variation of less than two percent if the area ratios of inlet to discharge is greater than five or six to one.

It has also been found that the tubes like those shown in FIGURES 11 to 14 inclusive utilizing the double wall insulating characteristics, ensure only a slight decrease in the temperature of the fluid from the inlet end to the closed end of the tube, which varies with the inside and outside temperature and the quantity of air flowing through the tube.

It will be understood that the baffling means embodying the invention can be used in extremely wide tubes fed with heated supply air from both ends, which would have the same relative effect as a tube of half the length which was fed from one end. Also, with a tube fed from both ends, as shown, for example, in FIGURE 10 of my co-pending application Serial No. 968, now Patent No. 3,036,385, there could be two identical baffle units, for example, like the one shown in FIGURES 2 and 6 of the present application, one at each end of the distributing tube with its inlet end communicating with the inlet end of the tube.

While several structural embodiments of the invention have been illustrated and described, it should be understood by those skilled in the art that the details of construction of the distributing tubes may be widely modified and changed and that the invention may be embodied in other types of fluid-distributing tubes as well as in fluid-distributing tubes for other purposes, within the spirit and scope of the invention.

I claim:

1. A fluid distributing tube for use in apparatus for treating material with a heated gaseous fluid, said tube having at least one inlet at an end thereof for connection to a supply of heated fluid under pressure and also having an outlet extending longitudinally of the tube between said inlet and the other end of the tube, and means comprising a baffle inside said tube having walls spaced from the side walls of the tube substantially throughout the length of the outlet forming fluid spaces between the baffle walls and the walls of said tube and also forming an inlet passage for fluid from said inlet to said outlet, said baffle walls providing between them and the relatively cool outer walls of said tube paths along the length of said baffle

walls each directly from said inlet passage to said outlet, the lengths of which paths along said outer walls from said inlet passage to said outlet gradually decrease from said inlet to the point in said outlet farthest from said inlet, providing for maintenance of the temperature of the fluid from said inlet substantially uniform from said inlet to the point in the outlet farthest from the inlet throughout a wide range of temperature differences between the temperature of the fluid supply at the inlet and the temperature of the fluid outside the tube.

2. A fluid distributing tube as set forth in claim 1 having top, bottom and side walls and said outlet in the bottom wall, and wherein said baffle is channel shaped and has its bottom wall in spaced and parallel relation to the bottom wall of the tube in juxtaposition to said outlet, and the side walls of the channel are disposed in spaced and parallel relation to the corresponding side walls of the tube and decrease in height from the inlet end of the tube toward the other end thereof, and said baffle has a flange at its larger end coacting with the walls of the inlet end of the tube to cause the fluid to flow into the tube only through the baffle.

3. A fluid distributing tube as defined in claim 1 wherein said baffle is tubular and has one open end coincident with the inlet of the distributing tube and its other end closed, the side walls of the tubular baffle having outlet apertures the distances between which and the outlet gradually decrease from the inlet of the tube toward the point in the outlet farthest from the inlet.

4. A fluid distributing tube as defined in claim 3 wherein both the distributing tube and the tubular baffle are rectangular in cross-section, the outlet of the tube is in the bottom wall of the tube the outlet apertures nearer the inlet end of the tubular baffle are in a top wall of the baffle farthest from the discharge openings, other outlet apertures are disposed in the side walls of the tubular baffle and at distances from the outlet that decrease from the first-mentioned apertures toward the other end of the tube.

5. A fluid distributing tube as defined in claim 3 wherein both the distributing tube and the tubular baffle are rectangular in cross-section with top, bottom and side walls and said outlet of the tube is in the bottom wall of the tube, the outlet apertures of the baffle nearer the inlet end of the tube are in the top wall of the baffle farthest from the outlet, other outlet apertures are disposed in the side walls of the baffle and at distances from the outlet openings that decrease from the first-mentioned apertures toward the other end of the tube, and the bottom wall of the baffle has outlet apertures adjacent the second-mentioned end of the tube and extending diagonally thereof from said side wall of the baffle toward the other side.
